UNITED STATES PATENT OFFICE.

ANDREW F. BARRON, OF WATERVLIET, NEW YORK.

CLOSET-BOWL.

1,182,735.

Specification of Letters Patent.

Patented May 9, 1916.

Application filed May 7, 1915. Serial No. 26,590.

To all whom it may concern:

Be it known that I, ANDREW F. BARRON, a citizen of the the United States, residing at Watervliet, in the county of Albany and 5 State of New York, have invented certain new and useful Improvements in Closet-Bowls; and I do hereby declare the following to be a full, clear, and exact description of the invention, such as will enable others 10 skilled in the art to which it appertains to make and use the same.

This invention relates to closet bowls, and the primary object of the invention is to provide a closet bowl which is constructed 15 so as to carry away the obnoxious odor which arises after the use of bowl, and also to provide means for efficiently flushing the bowl for preventing the accumulation of paper or the like therein, and to increase 20 the sanitary proclivities of the bowl.

Another object of this invention is to provide auxiliary air passages, which lead from the shoulder of the bowl rearwardly, to the rear edge of the same, for carrying 25 off the odor from the bowl.

With the foregoing and other objects in view this invention consists in such novel features of construction, combination and arrangement of parts as will be hereinafter 30 more fully described, illustrated in the accompanying drawings and claimed.

In describing the invention in detail reference will be had to the accompanying drawings wherein like characters designate 35 like or corresponding parts throughout the several views, and in which:—

Figure 1 is a side elevation of the improved closet bowl, Fig. 2 is a vertical section through the bowl, and Fig. 3 is a detail sectional view of a part of the construction of the bowl.

Referring more particularly to the drawings, 1 designates the commode or closet bowl, which has a base 2 secured to the 45 lower edge thereof, for attaching the bowl to the floor of a room, and which has an upper seat portion 3, formed upon the upper end of the bowl body 1. The bowl 1 has the ordinary flush tube 4 mounted about the seat section 3, which tube is provided with a plurality of circumferentially spaced openings 5, for permitting of the flow of water into all parts of the bowl for the purpose of flushing the same. The 55 tube 4 has communication with the water

inlet opening 6 of the bowl in the ordinary manner, and it has a relatively short tube or nipple 7 formed thereon, at the forward portion thereof. The nipple 7 is provided with an opening 8 extending therethrough, 60 which has communication with the interior of the tube 4, and is provided for forcing a stream of water downwardly over the upper surface of the partition 9, formed within the bowl and forming the upper wall of 65 the trap 10 of the bowl, for preventing the accumulation of paper, or the like thereon.

The rear apron 11 has a tube 12 extending substantially vertically therethrough, which communicates with the passageway 6. The 70 tube 12 has its upper end slightly flared, and it is curved to conform to the curvature of the rear wall of the inner recess formed within the bowl. The tube 12 terminates a short distance below the lower edge of the 75 apron 11 and it rests against the rear wall 14 of the bowl, so that the water flowing therethrough will efficiently flush the rear wall of the bowl.

A tube 15 extends downwardly through 80 the rear section of the bowl 1, and it has communication with the passageway 6. The tube 15 extends downwardly, and has its lower end curved, so that its lower end will rest upon the bottom of the recess of the 85 bowl a short distance outwardly from the mouth of the trap 10, thereby facilitating the efficient flushing of the bowl, by forcing a stream of water outwardly at the mouth of the trap for aiding in forcing the 90 contents of the bowl into the trap and outwardly through the same, through the outlet pipe 16, which may be connected with any suitable type of sewerage construction.

The rear side of the bowl 1 has a projection 20 formed thereon, which is provided with an open space 21 formed therein. A pipe 22 communicates with the open space 21, and it may be constructed in any suitable manner, such as the ordinary type of nipple 95 used for forming air or fluid-tight connections between the closet bowl and the pipes leading thereto or therefrom. The pipe 22, which communicates with the space 21, is adapted for communication with any suitable type of vent pipe or passageway leading out of the building in which the bowl is mounted, and its purpose is for carrying away the obnoxious odor arising after the 100 use of the bowl.

The bowl 1 has projections 23 formed upon its opposite sides, which communicate with the interior of the bowl beneath the apron or tube 4 thereof, as is shown at 24. 5 The passageways 23 extend around the outside of the bowl 1 and have communication with the space 21, as is shown at 25, so that the odor from the bowl will pass around through the passageways and into the space 10 21 and out of the same through the vent openings. The vent opening or pipe, having atmospherical communication, will create a draft or air suction through the space 21 and the passageways 23, maintaining a 15 fresh and comparatively pure state of air within the closet bowl, thereby increasing the sanitary proclivities of the same, and preventing the passage of foul or obnoxious odor from the bowl into the room in which 20 the same is positioned.

In Fig. 3 of the drawings, one of the nipples, such as are employed for connecting the water flushing pipe and the air vent pipe 22 to the bowl is shown. This construction 25 includes a nipple 30, which has its lower or inner end 31 flared, for seating in the flared portions of the openings. The shank 31 of the nipple, which projects out of the bowl, is externally screw threaded, and a union 33 is mounted thereon and held in place by a lock nut 34, for forming a substantially fluid-tight connection between the pipe and the openings in the bowl. 30

In reducing the invention to practice, certain minor features of construction, combination, and arrangement of parts may necessitate alteration, to which the patentee is entitled, provided such alterations are comprehended within the scope of what is claimed. 35

Copies of this patent may be obtained for five cents each, by addressing the "Commissioner of Patents, Washington, D. C."

What is claimed is:—

In a closet bowl structure, a closet bowl having a seat section, a flushing tube extending about said seat section, an apron partitioned within said bowl adjacent to the back thereof, said closet bowl being provided with a water inlet opening, a trap structure in said bowl, an arcuate tube carried by the rear portion of said bowl and having its lower end resting upon the upper surface of the bottom of the recess formed within the bowl, a relatively short distance outwardly from the mouth of said trap structure, the upper end of said tube communicating with said water inlet opening, the lower end of said tube being positioned for ejecting a stream of water over the bottom of the recess of the bowl, a second tube extending downwardly through said apron and being curved to conform to the curvature of the upper portion of the rear wall of the recess formed within the bowl, said relatively short tube having its upper end flared and communicating with the water inlet opening for conveying a stream of water for discharge along the rear wall of the recess of the bowl, said bowl being provided with an air space formed therein rearwardly of said tubes, said bowl having openings formed in the side thereof forwardly of said air space, and extensions formed upon the outer surface of said bowl and connecting said vent opening with said air space.

In testimony whereof I affix my signature in presence of two witnesses.

ANDREW F. BARRON.
